APPARATUS FOR SORTING POSTAL PACKETS

James Frederick Doust, London, England

Application January 12, 1948, Serial No. 1,781
In Great Britain December 31, 1946Section 1, Public Law 690, August 8, 1946
Patent expires December 31, 1966

6 Claims. (Cl. 209—111)

1

It is known in sorting postal packets for an operator to cause any particular packet to be deposited in one of a number of boxes forming an endless conveyor each of which is provided with trips which the operator sets by a code according to the destination of the packet, the trips so set causing the box to open above the chute or compartment appropriate to the destination in question. This method has the drawback that the operations of converting the destination into a code and of sorting the packets are combined in a single machine. By the present invention, the operations of coding and sorting are dissociated from each other, thus enabling both to be carried out with greater efficiency, and also enabling the sorting to be performed at any convenient location which may, if desired, be remote from the coding office.

The invention consists in a method of sorting postal packets which comprises applying to each packet a set of substantially invisible or transparent marks of fluorescent material of which the position, number and/or emitted wave band is related to the destination of the packet by a code, and conveying the packets so marked to sorting means or to a succession of sorting means comprising, or each comprising, means for projecting exciting radiation on the marks, photoelectric means for detecting the emitted radiation, and a code reading device adapted to be operated by the output of the said photoelectric means so as to control a directing device for sorting the packets according to their destinations.

The term "fluorescent material" as used herein means a material which, when subjected to radiation capable of exciting it, fluoresces to a substantially greater extent than the envelope or wrapping to which it is applied.

In an advantageous application of the invention, the set of marks applied to each packet comprises a number of series of marks, each series of marks being related to one item of the address on the packet, and the packets are then conveyed to sorting means which sort them into batches according to the first item of the address. Each batch is then conveyed to sub-sorting means which sort the articles according to the second item of the address, and so on. Thus, for example, the packets may be sorted by the first sorting means according to main towns or postal regions. Each batch is then conveyed to its appropriate regional office where it is fed to the second sorting means which sorts the packets into postal sub-regions. No further coding is necessary at the regional office since both the region and the sub-region have been coded at the

2

original coding office. This process can be continued until each packet is sorted to its final destination, but only if the marks are applied to the packet by the consignor, who would have to be aware of the code appropriate to the full addresses of a number of individual consignees. To enable the consignor to apply the code, coding machines may be provided for use by the general public, for example in private premises or kiosks. Such machines may be coin-free, in which case they may be adapted to apply a franking mark to the packet in addition to the code.

The marks may be of any convenient shape, for example rectangles, circles or dashes, and any convenient code may be used. Where only one type of fluorescent material is used, the code is in binary scale, that is consisting of combinations of marks and spaces.

The packets may preferably be scanned by a fixed source of light and a fixed photoelectric cell while they are in motion from the stack of coded packets to the directing device. In this case an advantageous method of sampling the output of the photoelectric cell approximately at the centre of each code mark or space consists in arranging that the code reading device is triggered into operation by the differentiated output of a photoelectric cell illuminated by a beam of light which is increased or decreased in intensity in steps by the advancing envelope in such a manner that an increase or decrease occurs each time the centre, or approximately the centre, of a code mark or space passes the scanning position.

The invention also includes apparatus for carrying out the method described in the preceding paragraph which comprises means for conveying a succession of postal packets through a scanning position, means for projecting a beam of exciting radiation on the code marks on the packets at the scanning position, a scanning photoelectric cell arranged to receive fluorescent radiation emitted by the code marks, a code-reading device adapted, when triggered, to be operated by the output of the scanning photoelectric cell, and a triggering photoelectric cell which is connected with the code-reading device through a differentiating circuit so that its differentiated output triggers the code-reading device, and is illuminated by a beam of light passing through a mask having a plurality of apertures and situated adjacent to the path of the postal packets, the number and position of the apertures being such that each packet covers or uncovers the apertures in succession so that the intensity of the light falling on the triggering photoelectric cell decreases or increases in steps each time the

centre, or approximately the centre, of a code mark or space passes the scanning position.

The source of exciting radiation may preferably be intermittent in order that the output from the photoelectric cell may be alternating, and therefore more easy to amplify. The intermittent radiation may be furnished by a lamp of the gas discharge type fed with alternating current, or by a continuous source of radiation having a mechanical interruptor.

Suitable fluorescent materials are, for example, the sodium salt of 4:4'-di-(para-aminobenzoyl-amino) - stilbene - 2:2' - disulphonic acid, that known by the trade name Primuline (Colour Index No. 812), fluorescein, and eosin. These materials fluoresce under ultra-violet radiation, the colour of the emitted radiation being blue in the case of the sodium salt of 4:4'-di-(para-aminobenzoyl-amino)-stilbene - 2:2' - disulphonic acid, blue-white in the case of Primuline, green in the case of fluorescein, and yellow in the case of eosin. The colours in daylight of these materials are, respectively, colourless, primrose yellow, yellow, and pink. The materials are effective in extremely thin layers, obtainable, for example, by applying them to the packet in the form of 0.1 per cent aqueous solutions, so that the applied marks are either invisible (in the case of the sodium salt of 4:4'-di-(para-aminobenzoyl-amino)-stilbene - 2:2' - disulphonic acid) or faintly coloured transparencies in the case of Primuline, fluorescein and eosin.

A suitable source of radiation, is, for example, a mercury vapour discharge lamp, for example a 125-watt medium-pressure lamp enclosed in a bulb of filter glass which transmits only the ultra-violet radiation. Practically all the radiation emitted from a lamp of this kind has a wavelength in the region of 3650 Angstrom units.

Most grades of paper used for stationery fluoresce to a small extent, but their fluorescence is negligible in comparison with that of the fluorescent materials described above. Thus, for example, the fluorescence of these materials, when exposed to radiation of wave-length 3650 Angstrom units, is of the order of 50 times that of an ordinary white envelope when exposed to the same radiation.

The invention is illustrated by way of example by the accompanying drawings, in which

Fig. 1 represents an envelope bearing marks of fluorescent material,

Fig. 2 is a diagrammatic view of the means for scanning the marks and sorting the letters,

Fig. 3 is a graph of the output of the scanning photoelectric cell,

Fig. 4 is a schematic diagram illustrating the operation of the system.

Referring to the drawings, the marks 1 of fluorescent material on the envelope 10 are combined with blank spaces 2 so as to represent the destination of the letter in a binary code. Each of the rectangles 1 and 2 is described herein as a "code area." The envelopes 10 are placed on edge on a horizontal belt 11 which is carried on rollers 12 and moves in the direction of the arrow in Fig. 2 at a high speed, for example 500 feet per minute. The envelopes are supported by stationary vertical members 13 and pass between two lenses 3a and 3b between which is situated a fixed slotted mask 4. The lens 3a projects a beam derived from a metal filament lamp 5 through the slots of the mask 4, and the lens 3b focusses this beam on a triggering photocell 6.

An ultra-violet lamp 7 emits a beam of radia-

tion capable of exciting the fluorescent material, and the beam is focussed on the envelope 10 by a compound lens 8. Some of the radiation emitted by the fluorescent marks falls on the photocell 9, the output of which is used to operate code-reading means described below.

Situated adjacent to the belt 11 are a number of diverters 14. In the apparatus described, the number of diverters is assumed to be sixteen, 10 corresponding with the four code areas shown in Fig. 1 but the number of diverters could be increased to any desired figure by suitably increasing the number of code areas making up the code on the envelope. Each diverter 15 comprises an electro-magnet consisting of coils 15, a yoke 16 and a pole piece 17, and an armature 18 pivoted at 19 and carrying a diverter blade 20. As described below, when any given envelope has been scanned, the coils 20 of one of the diverters 20 appropriate to the fluorescent code on that envelope are energised through connections not shown in Fig. 2. The armature 18 and blade 20 of that diverter then turn in the clockwise direction, and when the envelope in question meets the operated 25 blade 20, it is diverted thereby from the belt 11 into a sorting box 21. In Fig. 2, the second diverter blade from the right is shown in the operated position. Upon deenergisation of the coils 15 through the agency of re-setting signals 30 described below, the blade 20 is returned to its normal position by a spring 30.

Fig. 3 is a graph, not drawn to scale, illustrating the voltage output from the photocell 9 as the code passes the scanning position, the lamp 7 being run on an alternating current of frequency 1600 cycles per second. The ratio of the output corresponding with the fluorescent marks to the background output is of the order of 30 decibels, if the type of photocell is correctly chosen.

The object of the mask 4 and triggering photocell 6 is to provide a timing system, which is independent of the speed of the envelope, for triggering the code-reading means as described below as the centre of each mark or space 1 or 2 passes the scanning position. As the envelope advances, it covers each of the slots of the mask 4 in succession. The code is placed in a standard position on each envelope (shown as the bottom left corner) and the mask 4 is so arranged that as the centre of the first mark or space passes the scanning position, the leading edge of the envelope covers the first slot of the mask 4, as the centre of the second mark or space passes the scanning position, the leading edge of the envelope covers the second slot, and so on. The light falling on the triggering photocell 6 is thus reduced in intensity by one step each time the centre of a mark or space passes the scanning position.

The output of the photocell 6 is passed into a differentiating circuit the output of which is used to trigger the code-reading device. The latter is thus operated by the output of the photocell 9 at the centre of each mark or space, which is independent of any indefiniteness or malformation at the edges of the marks.

It will be appreciated that the slotted mask 4 could be arranged in advance of the scanning position, so that as the envelope advanced it would uncover the slots successively, thus increasing the intensity of illumination of the photocell 6 in steps instead of decreasing it. In this case the code would be placed in a predetermined position relatively to the trailing instead of the lead-

ing edge of the envelope. To avoid repetition of claims, therefore, where one of these arrangements is specified in any of the appended claims, the other is to be understood as an equivalent thereof.

As above noted, the details of the particular form of code reading device, and the particular details of the triggering circuit therefor, form no part of the present invention, and these old elements, *per se*, may be of any known form, the invention herein residing in the combining of the binary response of the code reading photocell 9 with the differentiated action of the triggering photocell 6 to render the permutation of the code readable and translatable to energize one of a number of director actuating circuits determined by the permutations of the code, while the coded letter is moving and independently of its speed.

In the U. S. patent to Ayres et al. No. 2,056,382 issued October 6, 1936, for example, six mark and space elements are applied to the letter in two rows each having three code areas therein and each arranged transversely of the direction of movement of the envelope. In that system the rows of code areas are scanned by apertures in a fixedly positioned rotating disc and the letter has to be held stationary during the scanning. That system further includes a code reading device having a triggered relay selector comprising a rotary switch (designated 20 by Ayres et al.) mechanically triggered or driven in synchronism with the rotating disc (16 therein), for sequentially connecting the code reading photocell to and disconnecting it from six holding-relay circuits (23 therein), of a binary permutation switch (30-31 therein) there being one holding relay for each code area. The energizing or non-energizing of each of the six holding relays by the code reading photocell (designated 17 in Ayres et al.) in response to the presence of a space or mark in the corresponding code area on the envelope, occurring as the arm of the rotary switch (28 therein) passes across its contacts, establishes a circuit from a source of power through the banks of permutation contacts of the permutation switch (30-31 therein) and energizes that single one of thirty-two director controlling circuits (32 therein) corresponding to the permutations of marks and spaces in the 6-element binary code area on the letter.

Such a system may be employed in practicing the present invention, in which case (1) the photocell 17 of Ayres et al., corresponding to the code-reading photocell 9 in the present disclosure, may be located to scan the single row of binary code elements moving therewith as indicated in Fig. 2, herein, and (2) the triggered switch 20 of Ayres et al. may be moved across its contacts to momentarily connect the cell 9 to the respective holding-relay circuits, not by driving it synchronously with a scanning disc as in Ayres et al., but by stepping it in response to each change in output of the photocell 6 produced by the advance of the leading edge of the envelope across the mask 4. The differentiating circuit hereinabove mentioned, well known *per se*, as its name implies is a circuit that produces a constant output as long as its input remains steady at any level, and which increases its output only while the input is changing. An ordinary transformer is one example, since with a D. C. input it produces a pulse of output during each period of change of input, and such output pulses may be employed to trigger the stepping of the switch 20 of the Ayres et al. system as in the stepping of

any known form of selector or stepping switch, one example of which is shown *per se* in the patent to Kermode et al. No. 1,985,035, dated December 18, 1934.

Accordingly, with the triggering of this known form of permutation code reading device by the differentiated output of the triggering photocell 6 as herein disclosed, the operation of the system may take place in the manner indicated in the 10 schematic diagram, Fig. 4, namely:

(A) As the envelope, with mark and space coding positioned in definite spaced relation to its leading edge, enters the conveyor, the first coding element 1 (Fig. 1) comes into position to be 15 energized by source 7 (Fig. 1) and if marked, illuminates code reading photocell 9. (B) As the centered position for such illumination is reached, the leading edge of the envelope closes the first opening in the mask 4 (Fig. 2) and the output of 20 the triggering photocell 6 is reduced one step, as at a. This reduction in output being fed to a conventional differentiating circuit (C) produces a differentiated output or pulse of energy, as b, which triggers or renders transiently responsive 25 to the output of code-reading tube 9 the actuating circuit C' of a first holding relay D' corresponding to the first code element being read by photocell 9. As in the patent to Ayres et al., for purposes of illustration the transient energization or 30 non-energization of holding relay D' may effect or maintain the closing of certain groups of contacts in the permutation switch-bank E, depending on whether or not the photocell 9 is energized by the code element scanned.

As the second, third and fourth code areas 1, 2 35 each become centered with the code reading photocell 9, the leading edge of the envelope repeatedly reduces the output of triggering photocell 6, and the differentiator C repeatedly pulses 40 the triggering circuit, thus triggering or transiently connecting the output derived from the reading of the code areas by the photocell 9 to the respective conductive paths C², C³, C⁴ leading to the stick relay D², D³, or D⁴ corresponding to 45 the respective code area. When the presence of a mark or space in each of the code areas has thus been registered by energization or non-energization of the holding relays D¹-D⁴ of the conventional permutation switch E, that output 50 circuit of the switch E, pre-determined by the permutations of marks and spaces thus registered is completed, and in turn operates that one of the directors 14 predetermined to correspond to the code combination appearing on the envelope.

As will be appreciated by those skilled in the 55 art, a code reading device may comprise either electro-mechanical stepping switches and relays, or electronic equivalents thereof cooperating with pulse actuable triggers of any type; and may comprise directly selected output circuits or output 60 circuits selected in any other manner, depending on the system used, and such details form no part of the present invention, which is not limited to the use of any particular type of code reading 65 devices, triggering devices, or diverters, as the invention resides in the new coordination of such means, and not in the details of the components, *per se*, which are herein illustrated merely for the purpose of aiding in the understanding of the 70 invention.

I claim:

1. In an improved apparatus for sorting postal articles, said articles being provided with article destinations coded on the respective articles by 75 detectable marks located in selected ones of a

series of several coding areas, the series of coding areas on each article being linearly arranged and spaced sequentially in a predetermined direction, code reading means triggerable to read selectively the coding in each of said several areas at distinct time intervals, triggering means for so triggering said code reading means, said code reading means including photoelectric mark-sensing means responsive to the presence or absence of marks in the respective ones of said several areas for operating said code reading means in its correspondingly triggered condition, said improved system being particularly characterized in that it includes conveying means for continuously moving the articles in a predetermined direction past the mark sensing means, and in that the triggering means for the code reading means is actuated by movement of the article by the conveying means in said predetermined direction for triggering said code reading means as such movement sequentially exhibits each of the respective ones of said several coding areas to said mark sensing means, and in that the triggering means comprises photo-cell means and light source means producing a series of light beams corresponding to the number of coding areas employed, said light beams being projected to said photo-cell means across the path through which said article is moved and being spaced longitudinally to be sequentially interrupted by the article as the article moves to exhibit sequential ones of said series of coding areas to said mark-sensing means, thereby to alter the output of said photo-cell means for triggering said code reading means.

2. An improved system for sorting postal articles according to claim 1, particularly characterized in that the triggering means comprises a single photo-cell means and a mask having a series of apertures therein through which said light beams project to said photo-cell means, said apertures being sequentially spaced on centers by distances equal to the spacings of the coding positions on the articles, and said mask being located so that the moving article cumulatively covers said apertures one at a time for each of the coding areas it exhibits to said mark-sensing means.

3. An improved system for sorting postal arti-

10

15

20

25

30

35

40

45

cles according to claim 2, particularly characterized in that said apertures are relatively narrow compared to the length of each of said coding areas in the predetermined direction of movement of the article, and in that said mask is positioned so that the covering of each aperture by the article synchronizes approximately with the centering of the corresponding area with respect to the photo-electric mark sensing means.

4. A system for sorting postal articles according to claim 3, in which said apertures are in the form of slots disposed parallel to the leading and trailing edges of postal articles being moved by said conveying means.

5. A system according to claim 1, in which said marks comprise fluorescent material, and in which said system comprises means for projecting exciting radiation on said coding areas as they are exhibited to the mark sensing means, and said mark sensing means comprises photo-cell means responsive to the fluorescence of said marks under said exciting radiation, said marks being substantially invisible under ordinary light.

6. A system according to claim 5, in which the means for projecting the exciting radiation operates to project said radiation intermittently so that said mark sensing photo-cell produces an amplifiable output.
